UNITED STATES PATENT OFFICE.

REINHOLD H. WAPPLER, OF NEW YORK, N. Y., ASSIGNOR TO WAPPLER ELECTRIC COMPANY, INC., A CORPORATION OF NEW YORK.

REFRACTING-STEREOSCOPE.

1,269,663.

Specification of Letters Patent. Patented June 18, 1918.

Application filed April 24, 1917. Serial No. 164,089.

To all whom it may concern:

Be it known that I, REINHOLD H. WAPPLER, a citizen of the United States, residing in the city of New York, borough of Manhattan, in the county and State of New York, have invented certain new and useful Improvements in Refracting-Stereoscopes, of which the following is a full, clear, and exact description.

10 My invention relates to stereoscopes, my more particular purpose being to produce a device of this character in which I use a pair of prisms so formed and arranged as to attain the following results:

15 I. To adapt the stereoscope for viewing pictures or images of large size, such as 14 by 18 inches, while retaining various advantages peculiar to the use of prisms.

II. To so direct the light rays that all of 20 those entering either eye are crossed rather abruptly by all of those entering the other eye, so that large pictures or images in pairs may be viewed at comparatively short range, the eyes of the observer meanwhile 25 remaining approximately normal in directive position—thus shortening the working distance and promoting compactness.

III. To render the device peculiarly adaptable for X-ray negatives or other pictures or images, using a translucent plate, illuminated by light applied to its back.

IV. To avoid the necessity for precise adjustment in various adjustable parts; to prevent all necessity for undue strain upon the 35 eyes of the observer incidental to use of the device; to prevent slight lateral displacement of the prism relatively to the picture or image from interfering with the stereoscopic vision; and to prevent or greatly 40 alleviate chromatic aberration.

These and other objects sought to be accomplished are explained more in detail in the descriptive matter to follow.

For the sake of conciseness I will describe 45 only a single form of my apparatus, it being understood, however, that this form is merely typical, and that the structure and action of my device may be varied within limits, defined by my claims.

50 Reference is made to the accompanying drawings forming a part of my invention, and in which like letters indicate like parts in all of the views.

Figure 1 is a perspective of my improved 55 stereoscope complete and ready for use.

Fig. 2 is a diagram for elucidating the optical principles involved.

Fig. 3 is a diagrammatic section through the prisms and casing for supporting the same.

A supporting tube 4 is mounted upon a spider 5, the latter being provided with leveling screws 6.

A supporting rod 7 extends into the supporting tube 4, and is detachably held by 65 a set screw 8 and thus rendered adjustable.

The rod 7 carries a clamping disk 9 integral with it. Mating this clamping disk 9 is another clamping disk 10. The clamping disks are forced together by a bolt 11 70 and wing nut 12. Carried by the clamping disk 10 is a rod 13, carrying a T 14. Extending from this T is a straight tube 15, and extending telescopically into the latter is an L-tube 16.

A rod 17 fits telescopically into the adjacent end of the L-tube, and is detachably held by a set screw 18. This rod 17 is adjustable relatively to the L-tube, and the L-tube is adjustable relatively to the straight 80 tube 16.

The rod 17 and all parts carried by it are adjustable angularly in relation to the rod 7.

A casing 19 is mounted rigidly upon the upper end of the rod 17, and serves as the 85 barrels of the stereoscope.

A pair of lanterns 20, 21, are provided with translucent plates 22, 23, which in this particular instance are X-ray negative plates. These negative plates are illuminated by the 90 lanterns, each of which contains one or more lamps, not shown. The lanterns are provided with hinge eyes 24, 25, which fit upon the rod 13, so that the lanterns can swing upon the axis of this rod as a center. 95

A pair of pitmen 26 are by pivot pins 27 connected to the lanterns, and by a single pivot pin 28 these pitmen are also connected to a sleeve 29, which is slidably mounted upon the straight tube 15. A set screw 30 100 holds the sleeve 29 normally fixed in relation to the tube 15.

The operator, by loosening the set screw 30, can loosen the sleeve 29, and by sliding this sleeve along the straight tube 15 and 105 tightening the set screw 30, he can adjust the lanterns 20, 21 and plates 22, 23. Thus the plates 22, 23 can be turned so as to be separated by different angles.

By adjusting the L-tube 16 relatively to 110

the straight tube 15, the distance of the casing 19 from the plates 22, 23 may be controlled, and by adjusting the rod 17 relatively to the L-tube 16 the altitude of the 5 casing relatively to the plates 22, 23 may be regulated at will.

Instead of the X-ray negatives 22, 23, pictures or images of any other type may be substituted, if desired, and the illumination 10 may be caused by the lanterns or by light from any suitable source. If ordinary photographs or analogous pictures are used, they need not be translucent and may be illuminated from the front—that is, upon 15 their exposed surfaces facing the casing 19.

The plates 22, 23 are in this instance quite large, say 14 by 18 inches, and are close together as well as close to the casing 19.

The casing 19 has a sheet metal body portion 32 and a portion 33 of arcuate form, 20 these parts being so disposed and arranged as to provide open slots 34, 35 serving as visual openings, the eyes of the observer being shown adjacent these openings, at 25 36, 37.

Two portions 38, 39 of sheet metal, integral with the casing, are bent inwardly or toward each other as shown in Fig. 3, in order to exclude the entrance of undesirable 30 light.

A pair of prisms are shown at 40, 41, each being provided with three flat facets 42, 43, 44, each having a distinct optical function. Each prism is also truncated to form a facet 35 45. The facets 45, 45 are practically idle and resting against the adjacent inturned portions 38, 39, of the casing.

The prisms are so fitted into the casing as to be held securely in position by the pressure 40 of the sheet metal top and bottom members of the casing upon the adjacent top and bottom surfaces of the prisms. Any suitable mechanical arrangement may be substituted, however, for holding the prisms 45 within the casing.

Each facet 42 is bare and throughout its entire surface is exposed to light entering through the large opening between the portions 38, 39 of the casing.

50 My purpose in truncating the prisms so as to form the two small facets 45 is to remove a portion of the prism which is not only useless but if allowed to remain would cause the two fields of view to interfere with each 55 other, and would also cause more or less chromatic aberration. By truncation of the prisms these undesirable effects are avoided and compactness is promoted by the shortening of the working distances from the 60 prisms to the pictures or images. Other dimensions being equal, the field of vision is thus enlarged.

No silvering or analogous surfacing is necessary for any of the facets 42, 43, 44.

65 It will be noted that each prism 40, 41 is

double acting. That is to say, it has three active or truly optical surfaces, and is so proportioned and arranged that the light in passing through it is twice reflected, and of course twice refracted. Thus many optical 70 faults peculiar to prisms of ordinary form are completely removed or greatly alleviated by the use of my improved prisms, owing to the fact that an optical fault due to internal reflection of light from one facet 75 may be compensated, neutralized or offset by internal reflection of the same light from a second facet.

I find it desirable that the angle between the facets 42 and 44 be double the angle between the facets 42 and 43. With the proportions just mentioned, and the parts arranged as shown and above described, the facet 43 reflects internally but does not refract, the facet 44 refracts but does not reflect, and the facet 42 both reflects and refracts; the portion of it adjacent the eye reflecting internally while the distal portion refracts and thus admits the light. 85

In order to trace the course of the light 90 rays through the prisms, reference is made to the lines 46, 47 and 48, which are representative of light rays. The plate 22 being illuminated as above described, light rays radiate from practically all parts of this 95 plate. Some of these light rays, represented by the lines 46, 47, 48, converge more or less and pass through the prism 40. They enter through the adjacent portion of the facet 42 and in so doing are refracted to 100 different extents, depending upon the angularity of the lines 46, 47, 48 relatively to the facet 42. As the rays reach the facet 43 they are reflected internally of the prism, and they continue to converge till they reach 105 facet 42. Here they are again reflected internally of the prism, and, still converging, they now pass out through the facet 44, being refracted in so doing, and enter the right eye 36 of the observer. Similarly the 110 rays represented by the lines 49, 50, 51 leave the illuminated plate 23, and pass through the prism, being twice refracted and twice reflected, yet all the while converging so as to enter the left eye 37 of the observer. 115

The net result is that the right eye 36, looking straight ahead, has a field of view commensurate with the entire operating surface of the plate 22, and the left eye 37 has a view commensurate with the operating surface of the plate 23.

The field of view represented by the lines 46, 47, 48 crosses the field of view represented by the lines 49, 50, 51 so that the two fields clear each other in the sense that each plate 22, 23 is visible in its entirety and that these plates do not overlap each other. Yet owing to the great angularity of the lines 46, 47, 48 relatively to the facet 42 of the prism 40, and of the lines 49, 50, 120 125 130

51 relatively to the facet 42 of the prism 41, the plates 22, 23, may be placed surprisingly close to the prisms, and may be of considerable size, as above explained. Of course, other things being equal, the longer the plates 22, 23 the farther they must be spaced from the prisms, but for a given distance from prisms to plates the plates may be relatively large, and for a given size of plates the distance from prisms to plates may be relatively short. Upon this account a slight increase in the distance from the prisms to the plates will enable the use of plates of much larger size than would otherwise be possible.

10 I do not deem it necessary to explain the well-known principle of the stereoscope, namely, the manner in which two pictures, each with a flat surface, are caused to virtually produce a single image having the attribute of perspective coupled with an apparent change in size and distance. Suffice it to say that in my stereoscope this general principle is the same as in any other.

15 I find that upon actual trial as well as upon theoretical considerations my stereoscope above described has all of the advantages above recited, as well as many others. Duplicate pictures, images or material objects, as the case may be, when seen through it, are remarkably clear in general outline as well as in detail. Any particular part may be closely scrutinized, as there is very little tendency toward confusion of lines, 20 conversion of straight lines into curves, or blurring of lights and shadows. Lateral displacement of the eyes of the observer relatively to the prisms has very little effect. In fact the operator while using the device may within reasonable limits move his head up or down or sidewise, or even give one of his eyes a slightly higher elevation than the other without materially disturbing his vision.

25 My improved stereoscope has no precise focal distance, and upon this account may be used with equal facility for enabling the operator to view objects of small size, placed close to the prisms, or objects of larger size, 30 placed farther away from the prisms. In many instances the objects can be seen to better advantage than would be the case if they were seen through spectacles or even through the naked eyes. Again, in some lines of development, such as X-ray work, it often happens that the pictures, and especially negatives, are large simply because they are shadowgraphs of objects which are themselves of considerable size. For instance an X-ray negative showing a man's 35 ribs must almost of necessity be of large size owing to the manner in which X-ray negatives are usually made. My prisms above described are well adapted for such negatives, because notwithstanding their

large size they can be brought into close proximity to the prisms and thus viewed to better advantage while, as above explained, compactness is promoted by the reduction in the working distance from the negatives 40 to the prisms.

45 Pictures, images or material objects seen through the stereoscope appear to be in every way normal. Directions such as right, left, up and down are not altered or varied 50 in any way. A person's right hand, for instance, would appear through the stereoscope as it would if seen by the naked eye.

55 I do not limit myself to the precise mechanism shown, as variations therefrom may be made without departing from the invention which is commensurate with my claims.

I claim:

1. In a stereoscope the combination, with means for supporting a pair of visual objects to be observed, of a pair of optical prisms each associated with one of said visual objects, each prism having a large facet and two smaller facets, each of said smaller facets being inclined relatively to 60 said large facet, the angle of inclination for one of said smaller facets being substantially double the angle of inclination of the other of said smaller facets.

2. In a device of the character described 65 the combination, with means for supporting a pair of visual objects to be observed stereoscopically, of a pair of optical prisms each associated with one of said objects, each prism being provided with a plurality 70 of facets so distributed that a group of convergent light rays in passing from the visual object through the prism to the eye of the spectator, is refracted in entering and also in leaving said prism and is twice 75 reflected internally thereof, said prisms being so located relatively to each other and to the objects to be observed that the group of convergent light rays from one of said objects is crossed by the group of convergent 80 light rays from the other of said objects.

3. In a device of the character described the combination of a pair of pictures and a pair of prisms for viewing said pictures stereoscopically, said prisms being so formed 85 and so located relatively to said pictures that a group of convergent rays of light passing from one of said pictures through its corresponding prism is crossed by a group of convergent rays of light passing 90 from the other of said pictures through the other of said prisms, and means for adjusting said pictures to different angles relatively to each other.

4. In a device of the character described 95 the combination of a pair of pictures and a pair of prisms for viewing the same stereoscopically, said prisms being so formed and so located relatively to said pictures that a group of convergent light rays passing from 100

one of said pictures through its corresponding prism is crossed by a group of convergent light rays passing from the other of said pictures through the other of said prisms, 5 mechanism for spacing said pictures at different distances from said prisms, and means for turning said pictures to different angles relatively to each other, in order to render said pictures normal relatively to said 10 prisms when thus spaced at different distances from said prisms.

5. In a stereoscope the combination of a pair of visual objects to be observed and a pair of prisms for viewing the same stereoscopically, each prism being provided with facets so arranged that light, in passing from either of said objects through the prism associated therewith is twice reflected and twice refracted, each prism being truncated 15 in order to prevent the visual object associated with one prism from being seen through the prism.

6. In a stereoscope the combination of means for supporting a pair of visual objects, a pair of prisms for viewing said ob- 20

jects stereoscopically, each prism having facets so distributed as to cause light, in passing from the object through its corresponding prism, to be twice reflected and twice refracted, each prism being truncated, 30 and means for preventing the entrance of light into the prism at the point where it is thus truncated.

7. In a device of the character described the combination, with means for supporting a visual object to be observed, of an optical prism provided with a large facet and with a plurality of smaller facets, all of said facets being so inclined relatively to each other and said prism being so positioned relatively to said visual object, that a group of light rays, in passing from the visual object to the eye of the spectator, enters the prism through a portion of the larger facet, is reflected internally of the prism by one of the smaller facets and also by a portion of said larger facet and leaves the prism by passing out through another of said smaller facets. 40

REINHOLD H. WAPPLER.
